D. J. BRIMM, JR

FLYING BOAT HULL

Filed Feb. 10, 1928

UNITED STATES PATENT OFFICE.

DANIEL J. BRIMM, JR., OF WEST HEMPSTEAD, NEW YORK, ASSIGNOR TO IRELAND AIR-CRAFT INCORPORATED, A CORPORATION OF NEW YORK.

FLYING-BOAT HULL.

Application filed February 10, 1928. Serial No. 253,273.

My invention relates to a system of float construction in which metal tubing, preferably steel, is employed; and an object of the invention is to provide structural combinations and details of special value in the construction of flying boat hulls, whereby a maximum of strength and rigidity is secured with a minimum of weight and material.

Heretofore, in the construction of metal flying boat hulls or the like, it has been the practice to rivet the outer metal skin or sheet metal covering of the hull directly to the hull or skeleton frame. Such hull frame generally comprises a built-up skeleton in which the longitudinal, transverse and diagonal members thereof are constructed of sheet metal of various section—flat metal stock being used in fabricating the various members of the frame.

Notwithstanding certain advantages resulting from the use of flat stock or sheet metal frame members, hull frames thus constructed are extremely complicated and cannot under any circumstances be produced in quantity except at a prohibitive cost. The various frame members are not commercially procurable; each member must be formed or shaped up from a flat stock sheet or strip; at the various joints in the hull frame gussets or fillet pieces are necessary; and where a light metal such as aluminum or duralumin is used, riveted, rather than welded joints, are required to be made.

The present invention, as distinguished from the above, contemplates a float or hull skeleton in which all of the principal, longitudinal, transverse, and diagonal members of the frame, are formed of commercially procurable tubular steel of closed hollow section throughout; in which all of said frame members are welded at their points of intersection; and in which the outer skin is directly fastened to the hull frame by suitable clips riveted or otherwise fastened to the skin and extending on the inside thereof around the tubular frame members constituting the skeleton frame. An all metal hull thus constructed is stronger per unit of weight; lighter; infinitely less complicated; better adapted to quantity production; and very much cheaper than any acceptable metal float heretofore designed. As indicative of the desirability of using metal tubing of closed hollow section

throughout in aeroplane construction, it may be conservatively stated that practically all modern fuselages, bodies, etc., other than floats, embody a similarly constructed skeleton frame. No one, however, in so far as I am aware, has found it either practical or expedient to use metal tubing substantially throughout in the design or construction of an aeroplane float or hull. The use, therefore, of metal tubing, in the fabrication of a hull or float frame, is not only desirable but extremely advantageous for the reasons herein set forth.

Other and further advantages of the invention, such, for instance, as the method of attaching the outer skin or sheet metal covering to the skeleton frame, will be hereinafter explained.

In the drawings, wherein like reference characters denote like or corresponding parts,

Fig. 1 is a side elevation of the hull frame stripped of its outer covering;

Fig. 2 is a plan view of the frame;

Fig. 3 is an enlarged transverse vertical sectional view on the line 3—3 of Fig. 1, and

Figs. 4, 5, 6, and 7, are fragmentary sectional views showing the manner in which the outer skin is attached.

In the embodiment of the invention selected for illustration, a flying boat hull of more or less conventional appearance is shown. It comprises a fore-body 10 and a tail extension 11. The underside of the fore-body 10 is of V-section throughout and terminates aft in a vertical step 12. From the step 12 rearwardly, the hull bottom is preferably substantially flat and may or may not be provided with a second vertical step 13. That portion of the bottom surface ahead of the step 12 constitutes the hydroplaning bottom surface of the hull.

The hull frame from bow to stern, comprises four principal longitudinal members or longérons, i. e., two upper and two lower. These principal longitudinal members are formed of metal tubing of closed hollow section throughout. The upper two constitute the gunwale stringers and the lower two the chine stringers of the hull frame. The gunwale stringers, designated as 14, from a point of intersection at the bow, curve outwardly to a point substantially amidships, and thence approach one another uniformly and grad-

ually to a point of intersection at the stern. The chine stringers, designated as 15, are similarly curved, except that amidships they are spaced further apart and at the bow do 5 not extend quite so far forward as the gunwale stringers 14. While the gunwale stringers may be formed, each from a single length of metal tubing, the chine stringers because 10 of the steps 12 and 13, are preferably formed of separate lengths, said lengths, at the steps, being extended one beyond the other as shown.

From end to end the corresponding gunwale and chine stringers are connected by 15 suitable vertical side frame members 15' and diagonal side frame members 16, said vertical and diagonal frame members being likewise of hollow or tubular section from end to end and welded at their ends or points of intersection to the stringers which they join. Top 20 transverse frame members 17 and top diagonal frame members 18 extend from one to the other of the gunwale stringers 14 throughout the length of the tail portion of the hull, and 25 bottom transverse frame members 19 and bottom diagonal frame members 20 extend from one to the other of the chine stringers 15. These frame members 17, 18, 19 and 20 are likewise of hollow section throughout and 30 are welded to the longitudinal frame members which they join. As the top side of the hull, forward of the tail portion 11 thereof, has formed therein suitable cockpits (not shown) the diagonal frame members, 35 throughout such portion of the hull length, are dispensed with. Two transverse frame members 21, however, are provided.

In addition to the chine stringers 15, the bottom of the hull frame, forward of the step, 40 comprises a keel 22 and a plurality of transversely extending frames 23. The keel at its forward end is carried upwardly on an easy curve to a point of intersection with the gunwale stringers 14 and at its opposite end terminates abruptly at the step. The frames 23, 45 unlike the remaining transverse frame members, are preferably formed of sheet metal. Each frame, (see Fig. 3) is of triangular shape and at its three included angles is fastened respectively to the chine stringers 15 and to the keel 22. The means of attaching or fastening the frames 23 to the chine stringers 14 comprises suitable gussets 24 welded to the chine stringers, to which gussets the frames 23 are riveted. The top edges of the 55 several frames afford bearing surfaces upon which the hull floor (not shown) is adapted to rest.

To prevent the equal distribution of water 60 throughout the full length of the hull in the event of leakage, three full depth bulkhead members are provided. These bulkheads are designated respectively 25, 26, and 27. The forward bulkhead 25 is located at 65 or near the bow, the intermediate bulkhead

26 in vertical alignment with the step 12, and the rear bulkhead 27 in vertical alignment with the step 13.

It will be seen from the above, that the hull frame in its entirety, except for the 70 transverse frames 23, is constructed of metal tubing of closed hollow section from end to end. To such frame the outer sheet metal covering or skin is attached. Only seven sheets of skin covering are required to be 75 used; four on the bottom of the hull, two on the sides thereof, and one at the top. The side cover sheets preferably extend from the gunwale stringers to the chine stringers and from bow to stern. The top cover sheet 80 extends from one to the other of the gunwale stringers, and from a point just back of the step 12 to the stern, whereas the bottom cover sheets extend from one to the other of the chine stringers back of the step 12 85 and from the chine stringers to the keel forward of the step 12. Where a step 13 is provided the rear bottom cover sheets extend respectively from step to step and from the step 13 to the stern. 90

The means for attaching the cover sheets to the skeleton frame comprises a multiplicity of clips 28 and 29. The clips 28 (see Figs. 4 and 5) are provided at intervals of space throughout the length of the stringers 95 14 and 15. At one end said clips 28 are riveted to the side cover sheets and at their opposite end they are riveted to either one or the other of the bottom cover sheets or to the top cover sheet depending upon whether 100 or not they are used for the attachment of the cover sheets to the gunwale or to the chine stringers. The fastening means in each instance comprises rivets 30 which penetrate the clip ends and the cover sheets. 105 The clips, intermediately of their ends, overlap and extend partly around the stringers, and where the material permits, may be welded thereto, or if welding is impractical, may be pinned thereto as indicated at 31. 110 The side and bottom cover sheets along their adjacent edges lie flat against the chine stringers 15. Over such adjacent edges a metal chine strip 32 is laid. This chine strip along its opposite edges is carried under the 115 bottom cover sheet and over the bottom edge of the side cover sheet and is riveted thereto; the rivets 30, where such rivets are provided, being carried thru several thicknesses of metal at the joint. Such strips, effect a 120 water-tight seal at the chines. The clips 29 are likewise carried on the inside of the skeleton frame and are spaced at intervals along the length of each transverse and each 125 diagonal frame member. These clips 29 are similarly welded or fastened to said frame members and are riveted as at 33 to the cover sheet held thereby. Where a deflector strip such as that indicated in Fig. 4, and designated 34, is provided, the rivets 30 may be 130

used to hold the clips for the deflector strip in place. This means of attaching the cover sheets to the skeleton frame avoids the necessity of penetrating the principal frame members and at the same time holds the cover sheets firmly to the frame. If desired, reinforcing strips 35 may be provided on the outer surface of the side cover sheets to act as a binder extending lengthwise the hull 10 frame.

A flying boat hull or other flotation body constructed as herein set forth may be produced in quantity at low cost; is strong and light; and is especially desirable by reason 15 of the novel form of skin fastening means employed. Moreover, the outer skin, in its relation to the chine and gunwale stringers, in each instance, lies tangent to that surface of the stringer against which the adjacent 20 edges of the cover sheets directly bear.

While I have described my invention in detail in its present preferred embodiment, it will be obvious to those skilled in the art after understanding my invention, that various 25 changes and modifications may be made therein without departing from the spirit or scope thereof. I aim in the appended claims to cover all such modifications and changes.

What I claim is:

30 1. A hull for flying boats including a skeleton frame comprising chine and deck stringers formed of metal tubing of closed hollow section throughout, an outer sheet metal covering for said frame, and means attached to 35 the inner face of the sheet metal covering for fastening it to the tubing of said frame.

2. A hull for flying boats including a skeleton frame comprising chine stringers, deck stringers, and hull side vertical and diagonal 40 members, said stringers and said members being formed of metal tubing of closed hollow section throughout, an outer sheet metal covering for said frame, and means attached to the inner face of the sheet metal covering and beneath which said stringers and said members are carried for fastening said covering to said frame.

3. A hull for flying boats including a skeleton frame and a sheet metal covering, the 50 skeleton frame comprising longitudinally extending and transversely extending frame members of metal tubing of closed hollow section throughout, joints uniting the frame members at their points of intersection, and 55 clips engaging the frame members and providing bearing surfaces, at intervals of space, throughout the length and depth of the skeleton frame for the attachment of said covering.

60 4. A hull for flying boats including a skeleton frame and a sheet metal covering, the skeleton frame comprising longitudinally extending and transversely extending frame members of metal tubing of closed hollow section 65 throughout, joints uniting the frame

members at their points of intersection, and clips partially encircling the frame members and extending off therefrom at opposite sides thereof to provide at intervals of space throughout the length and depth of the skeleton frame a multiplicity of bearing surfaces 70 against which said outer covering is fastened.

5. A hull for flying boats including a skeleton frame and a sheet metal covering, the skeleton frame comprising longitudinally extending and transversely extending frame members of metal tubing of closed hollow section throughout, joints uniting the frame members at their points of intersection, and clips fastened on the inside face of said outer covering and beneath which said frame members are carried to fasten said outer covering in place.

6. In a hull for flying boats, a skeleton frame of angular cross-section including a longitudinal stringer formed of metal tubing of closed hollow section throughout, a cover sheet bearing along one edge against one face of said stringer, a cover sheet bearing along one edge against a different face of said stringer, and a clip fastened to and extending from one to the other of said cover sheets on the inside of the skeleton frame, said clip for a portion of its length being in direct engagement with and fastened to said stringer.

7. In a hull for flying boats, a skeleton frame of angular cross-section including a chine stringer formed of metal tubing of closed hollow section throughout, a bottom 100 cover sheet bearing along one edge on the underside of said stringer, a side cover sheet bearing along one edge on the outer face of said stringer, and a clip fastened to and extending from one to the other of said cover sheets on the inside of the skeleton frame, said clip for a portion of its length being in direct engagement with and fastened to said chine stringer.

8. In a hull for flying boats, a skeleton 110 frame of angular cross-section including a longitudinal stringer formed of metal tubing of closed hollow section throughout, a cover sheet bearing along one edge against one face of said stringer, a cover sheet bearing along one edge against a different face of said stringer, a strip of angular cross-section extending lengthwise said stringer and beneath which the adjacent edges of said cover sheets are carried, and a clip fastened to and extending from one to the other of said cover sheets on the inside of the skeleton frame, said clip for a portion of its length, being in direct engagement with and fastened to said stringer.

9. In a hull for flying boats, a skeleton frame of angular cross-section including a longitudinal stringer formed of metal tubing of closed hollow section throughout, a cover sheet fastened along one edge thereof

to one face of said stringer, a cover sheet fastened along one edge thereof to a different face of said stringer, a strip of angular cross-section extending lengthwise said stringer and beneath which the adjacent edges of said cover sheets are carried, and clips spaced longitudinally of said stringer and fastened to said cover sheets on the inside of the skeleton frame, the clips, in each instance, being in direct engagement with and ¹⁰ fastened to said stringer.

In testimony whereof I hereunto affix my signature.

DANIEL J. BRIMM, Jr.
